METAL WORKING MACHINE

Robert S. Brown, New Britain, Conn., assignor,
by mesne assignments, to The New Britain-
Gridley Machine Company, New Britain, Conn.,
a corporation of Connecticut

Application September 19, 1928, Serial No. 306,908

95 Claims. (Cl. 29—38)

My invention relates generally to a metal working machine, and more particularly to an automatic station-type chucking machine.

Broad objects of the invention are to provide a machine of the character indicated for operating at a high rate of production and turning out work pieces of a high degree of accuracy; and generally to improve certain constructional and functional features of metal working machines and parts, and particularly those of the automatic chucking machine type, to facilitate operation and control and to increase the reliability of such machines.

It is a more specific object to provide a machine of the character indicated, for chucking and unchucking work pieces and controlling feed functions by a single operative means.

Another object is to provide improved threading mechanism by means of which both right and left hand threads may be formed, and the running off speed of the tap, die or thread chasers will be greater than the running on speed.

It is another object to provide improved thread control mechanism, which will be automatically actuated at fixed definite times, dependent upon length of thread and regardless of the condition of activity or inactivity of other normally connected feed functions of the machine.

A still further object is the provision of an improved thread leader mechanism for feeding multiple threading tools.

It is another object to provide thread leader mechanism which may be directly driven from a rotating part, such as a threading spindle.

Another object is the provision of means for manual feed of one tool and work piece relatively to each other in conjunction with other automatically actuated tools and work pieces.

It is a further object to provide a turret clamping means to permit adjustment of the clamping pressures from the outside of the machine.

Another object is to improve certain features of fluid pressure actuating devices employed for chucking work pieces.

A more specific object is to provide improved valve actuating mechanism for fluid pressure actuated chucking devices.

Another object is to provide an improved indexing mechanism for a turret.

Another object is to provide a unitary coolant reservoir and reservoir for fluid for chucking or other hydraulically actuated devices.

A further object is to provide improved forms of chucks and to organize a machine to permit ready interchangeability and operation of different types of chucks.

Other objects and the features of invention will hereinafter appear.

The invention, as indicated above, involves the improvement in construction or functional effect or both of a considerable number of different parts of a metal working machine, and some of these parts are of utility in connection with machines of different types.

For purposes of illustration only, the various features of invention will be described as embodied in an automatic chucking machine of the tool rotating type.

Briefly stated, in a preferred form of the invention, such as an automatic chucking machine, I employ a plurality of equidistantly spaced tool holders and a plurality of opposed work holders or chucks. The tool holders and work holders are fed relatively to each other to perform operations on work pieces held in the chucks, while the tools and work holders are rotated relatively to each other. If desired, one set of opposed work and tool holders may be fed relatively to each other by manual means, while the other tool and work holders are fed relatively to each other by automatic means.

Either the tool or work holders, but preferably the work holders, are indexed step by step, so as to successively bring each work holder into opposition to each tool holder, as is common in machines of the multiple spindle station type.

When required, threading operation may be performed at one station. I preferably provide means for rotating a threading spindle or spindles in the feeding direction at a relatively low speed, regardless of whether a right or left hand thread is being formed, and rotate the threading spindle or spindles in the running off direction at a relatively higher speed, regardless of the hand of thread being cut. The length of thread to be cut may be determined by stop means, which may stop rotation of the threading spindle when a thread of predetermined length has been formed. The running off movement of the threading spindle is preferably initiated by cam means, which act independently of the aforesaid stop means. The threading operation is also preferably initiated by cam means related to other feed functions of the machine, and I have provided improved means for permitting the stoppage of the threading spindle when the desired length of thread has

been cut or the threading tool has run off to the desired extent, regardless of the activity or inactivity of the other normally connected feed functions.

5 I have provided improved thread leader devices which may be directly gear driven from a rotating part, such as the threading spindle itself. I also provide improved thread leader mechanism for feeding independently a pair of 10 concentric spindles, preferably rotating together, and the thread leader mechanisms preferably being out of alignment with each other. My improved thread leader mechanism may be organized substantially as a unit, so as 15 to be readily detachable should threading operations be unnecessary on the particular work pieces being formed.

I may also provide for manually feeding a tool 20 and work holder relatively to each other, while the other tools and work holders are fed relatively to each other by automatic means. The manual feed device is preferably located for actuation in loading position of the machine. Such manual feed mechanism may be made 25 readily detachable, so that it may be removed when not required on any particular type of work pieces being formed.

For indexing the work and tool holders relatively to each other, I may employ a star wheel 30 and actuating arm, forming a Geneva motion, such as is often employed for indexing functions of metal working and other machines. When the indexable member is either adjustable or movable to different longitudinal positions, 35 I interconnect the star wheel and actuating arm, so that these elements remain in the proper operative relation, regardless of longitudinal positions, and the actuating arm may be driven by a long faced gear or pinion, providing 40 constant mesh with a driving gear.

The indexable member is preferably clamped in indexed position and so held by resilient means. The clamping devices are so organized that the force exerted by the resilient means 45 may be varied from the outside of the machine, so as to facilitate such variation or adjustment.

The turret and head stock portions of the machine may be aligned and guided relatively to each other by means of a rigid extension on 50 one of the members and bearing in the other member. This extension member rigid with either the turret or head stock may be adjustably connected to the other member so that the collective tool thrusts will be at least partially taken by the extension member. This construction makes for a more rigid construction, and work pieces of greater accuracy are turned out.

When work pieces are chucked by fluid pressure actuated means, I may employ a plurality of cylinders, one for each chuck. The valve arrangement is such that, whether or not individual valves are provided for each cylinder, the chuck in loading position or station may be 65 actuated while the chucks in work stations remain closed. The pressure fluid may be air or a liquid. When air is employed, any source of compressed air may be utilized. When a liquid, such as oil, is employed as the pressure fluid, I preferably drive a pump by some driven part of the machine, and of course provide a storage chamber for the suction side of the pump and for receiving the pressure fluid after it has been exhausted from the fluid pressure 75 sure actuated devices.

The valves, when individual valves are employed and the cylinders do not rotate as in the present illustrative machine, may be mounted directly upon the heads of the fluid actuated devices, and are preferably cam-controlled and are preferably held in position to maintain pressure fluid on the fluid pressure actuated devices at all times that the work pieces are being acted upon by tools. In the loading position the valves are actuated to unchuck the finished work pieces and subsequently chuck a new work piece. Such actuation of each valve in series may be performed automatically, but for large work pieces I prefer to provide manual means, which may actuate a part of the cam track normally holding the valves in definite position, so as to move each valve when it is in the loading station. In order to obviate the possibility of an open chuck colliding with a tool at any station, the valves may be automatically actuated to close each chuck before it comes opposite the first working station.

When the chuck actuating pressure fluid is a liquid, such as oil, I preferably provide a unitary reservoir in the base of the machine and divide 100 same to provide a chip separating reservoir for coolant and a reservoir for the pressure liquid. A coolant pump and a pump for pressure fluid may be driven together.

Various types of chucks may be employed in 105 my improved metal working machine. Screw chucks, for example, may be actuated by rack and pinion means, moved by the fluid pressure actuated devices, when such are employed. Collet chucks may likewise be employed and actuated by the same racks as would be employed for screw chucks. The rack for chuck actuation is preferably housed within the body of the chuck. I also provide improved means for varying the pressure exerted by chuck jaws in various positions, upon the application of a substantially uniform pressure to the chuck actuator.

In the drawings which show, for illustrative purposes only, preferred forms of the features of invention as embodied in an automatic chucking machine—

General description

The automatic chucking machine herein disclosed for illustrating the principles of the invention includes a base 1 having a head stock 2 and a turret 3. In the form shown, the head stock carries tools, while the turret carries chucks. The tools and chucks are rotatable relatively to each other, and the particular machine illustrated is of the tool-rotating type. The head stock 2 and turret 3 are indexible relatively to each other, for bringing each of a plurality of tools successively opposite each of a plurality of chucks. The machine may be driven by any

suitable means, such as a motor 4, mounted in the base of the frame. The chucks may be actuated by fluid pressure means, designated generally 5 and carried by the turret. The feed functions of the machine may be controlled by a lever 6, while chucking and unchucking may be under the control of a lever 7. In the preferred form the levers 6—7 are interconnected, so that, by actuating the lever 7 with one hand, the feed functions may be controlled, and chucking and unchucking likewise controlled.

Spindle drive

The motor 4 may be belt connected to a pulley 8 for driving the main drive shaft 9 (Fig. 5). A gear 10 on the shaft 9 may mesh with a gear 11 carried upon what I term the "No. 0" spindle shaft 12, which has preferably a spindle at the loading station of the turret. The No. 0 spindle shaft, as will be later described, may carry a spindle equipped for hand feeding. The shaft 12 drives a gear 13 mounted on a stub shaft carried by the head stock. The gear 13 meshes with a gear 14 on the intermediate spindle shaft 15. Through change gears 16—17 on the outside of the head stock the intermediate spindle drive shaft 15 drives the spindle drive shaft 18. Through a second set of change gears 19—20 the shaft 15 drives another spindle drive shaft 21. The shaft 12, through the gears 22—23, drives a shaft 24, which in turn carries a gear 25. The gear 25 meshes with gear 26 on an intermediate spindle drive shaft 27, which, through change gears 28—29 at the outside of the head stock, drives a spindle drive shaft 30.

The shaft 30 carries a gear 31, preferably spiral, which meshes with a corresponding gear 32 carried by and driving what I will term the "No. 1" spindle (Figs. 3, 4 and 5). The shaft 18 carries a gear 33, preferably spiral, meshing with a corresponding gear 34 on and driving what I term the "No. 2" spindle. The shaft 21 carries a gear 35, preferably spiral, meshing with a corresponding gear 36 on and driving what I term the "No. 3" spindle. The shaft 24 carries a gear 37, which may be, and preferably is, on a sleeve, which also carries the gear 23. The gear 37 may mesh with a gear 38 on shaft 39. The shaft 39, through change gears 40—41, drives the intermediate spindle drive shaft 42. Through gear 43 the shaft 42, carrying the meshing gear 44 on what I term the "No. 4" spindle, drives the latter.

All five spindles may thus be driven and, through change gears, the speed of all shafts may be varied, though, with the particular gearing arrangement shown, any change in the speed of No. 0 spindle, without substituting different change gears for all other spindles, will effect a change in the speed of all such other spindles.

In the machine herein disclosed the spindles may be arranged for cam feeding. The No. 1, 2 and 3 spindles are each provided with a cam follower member 45, carrying a cam roll member 46 for engagement by cams on cam drums 47 and 48. The cam follower members may be guided by means of angular guide bars 49, which may be slidably engaged by angular shaped portions on the cam follower members. The No. 4 spindle is likewise provided with a cam follower member 50, having a roller 51 or other cam engaging portion, and the follower member 50 may be guided by the guide bar 49, as shown. The No. 4 spindle, as will be later described, is arranged for threading when threading opera-

tions are to be performed by the machine. The drives for the cam drums will be later described. The No. 0 spindle which, as stated, is preferably opposite a chuck in the loading position, is 5 preferably slidably, but non-rotatably, carried by the No. 0 spindle shaft 12 as by a spline (Figs. 3, 4, 5 and 13). The No. 0 spindle is equipped for hand feeding, so that a hand drilling, reaming or other operation may be performed on a 10 work piece after it has been chucked in the loading position and before an indexing movement has carried the work piece to the next station. When the No. 0 spindle is used and equipped for hand feeding, I preferably attach 15 a bracket 52 (Fig. 13) to the face of the head stock and pivotally connect thereto a manually operable lever 53, having yoke members 54-54 engaging a spool 55 on the No. 0 spindle. Thus, by manually operating the lever 53 the No. 0 20 spindle may be fed while being rotated, as heretofore described. If desired, any suitable type of interlocking mechanism may be employed for withdrawing the No. 0 spindle from a work piece before the turret indexes or for preventing indexing of the turret while the No. 0 spindle is 25 advanced.

Threading spindle drives

30 The machine is arranged at one station for performing threading operations, though, if threading on any particular work piece is not required, other forming operations may be done at that station.

In the form shown the No. 4 spindle is arranged for threading. The threading operation is frequently the longest operation performed on a work piece, and consequently the production capacity of the machine is limited by such longest operation. Heretofore it has been common practice to revolve the threading spindle in the threading on direction at the proper threading speed, and then perform the run off at a relatively higher speed, for the sake of saving time. It has also been common practice, when cutting left-hand threads in a machine set up for normal right-hand threading, to employ the running off feed gear of the normal right-hand threading arrangement as the running on gear for left hand threading, and to 45 employ the normal right hand run on gear as the left hand running off gear. Consequently, when cutting left hand threads, the running off speed would be slower than the running on speed. If both the threading and running off gears were rotated at the same speed, both the running on and running off speeds would be the same.

I have devised exceedingly simple means for 60 performing both right and left hand threading operations at a proper speed, and to cause the run off speed to be higher, regardless of whether right or left hand threads are being cut.

One preferred embodiment has been disclosed 65 and shown more particularly in Figs. 3 to 9 inclusive. Referring more particularly to Fig. 5, which is a partly diagrammatic development view illustrating the drives for the No. 4 spindle, it will be recalled that the drive for the No. 4 70 spindle is from the No. 0 spindle shaft 12 through the gears 22-23, and in the full line positions of the gears, through the gears 37-38, the latter of which rotates the clutch part 60 on the threading spindle clutch shaft 39. With 75 the gear 38 clutched to the shaft 39, the drive

continues from shaft 39 through external change gears 40-41 to shaft 42, and through gears 43-44 to the No. 4 spindle. The above drive is that employed for the running on of the threading tools. The reverse or running off rotation of the No. 4 spindle is through the No. 0 spindle shaft 12 and gear 22, meshing directly with gear 61, carrying the reverse clutch part 62. With the clutch 60 freed and the clutch part 62 engaged the drive continues from gear 61, shaft 39 and through the external change gears 40-41, shaft 42, and gears 43-44, to cause the reverse rotation of the No. 4 spindle. It will be noted that the gearing is so proportioned that the running on speed controlled by the large gear 38 is relatively slow, while the running off speed controlled by the relatively smaller gear 61 is relatively high. Such would be the normal spindle drive for right hand threading operations.

Now, when a left hand thread is to be cut, the sleeve carrying the gears 22 and 63 on No. 0 spindle shaft 12 is shifted to the right or dot and dash line position shown in Fig. 5 and secured in such position by any suitable means. This shift will cause the previously free gear 63 to mesh directly with gear 38. The sleeve carrying the gears 23-37 is shifted to the left or dotted line position of Fig. 5, so as to cause the gear 37 to be disengaged from the gear 38 and to cause the gear 23 to mesh directly with the reverse gear 61. It will be observed that these shifts remove the idler gear 37 from between the shafts 12 and 39 and cause a direct meshing of gears 63 and 38, so as to cause a reverse rotation of gear 38 and consequently of No. 4 threading spindle when clutch 60 is engaged. These shifts also interpose the idler gear 23 between the driving gear 22 and the reverse gear 61, so as to cause a reverse rotation of the shaft 39, and consequently of the No. 4 spindle, when the clutch 62 is engaged. Thus, by the simple shifts of gears 22-63 and 23-37, the No. 4 spindle may be rotated for threading in either right or left hand direction through the same clutch and at a relatively slow speed, and cause the running off rotation of the No. 4 spindle to be either in the right or left hand direction, at a relatively higher speed, through the reverse clutch gear 61. Therefore, whether right or left hand threads 125 are being cut, the running off speed may always be performed at a higher rate than the running on or threading speed of the No. 4 or threading spindle.

Threading clutch shift lever

The threading clutch spool 64, shown in the neutral position in Figs. 5, 7 and 9, is moved to clutch either the forward threading gear 38 or the reverse threading gear 61 to the shaft 39, 135 by means of a threading clutch shift lever 65. In the preferred form illustrated, I employ cams, one of which is designated 66, for throwing the clutch shift lever so as to shift the spool 64 to the right, as viewed in Fig. 5, to connect the 140 spindle for a forward threading drive. If the threading spindle is to be fed in relatively to the work piece by the tap, die or thread chasers, without the use of thread leader mechanism, I may employ a second cam, for example, as 145 shown at 67, for engaging any suitable part of the threading spindle or part carried thereby, to bring the threading tool and work into engagement with each other, after which the spindle may be fed in relatively to the work piece by 150

the threading tool itself. When thread leader mechanism is employed, the cam 67 would not be used.

The threading clutch shift lever 65 may be thrown out by various means, but I prefer to throw the same by means controlled by movement of the threading tool, so that, when a definite length of thread has been cut, regardless of any cam which might be employed for throwing the lever, the latter will be definitely thrown to disengage the forward threading clutch and permit the threading spindle to stop. I also prefer to definitely separate the forward and reverse threading movements of the threading spindle, so that, at the end of the threading movement, an opportunity is afforded for readjusting parts for cutting a longer or shorter length of thread, as may be desired. After the machine has been set up and is turning out work pieces on a production basis, the reversal of the threading spindle is accomplished as soon as practicable after the required length of thread has been cut, in order to save time.

In the preferred form the reversal of the clutch shift lever 65 is accomplished by a cam (not shown) acting oppositely to the cam 66. The subsequent throwing of the lever 65 into neutral position is preferably accomplished by stop means, dependent upon the longitudinal movement of the threading tool, and this is more particularly so when thread leader mechanism is employed. The shift lever 65 is so arranged that, should the cam drums controlling other feed functions of the machine be stopped while the cam for moving the lever 65 is in engagement therewith, the lever or a part thereof may be thrown into neutral when the threading tool has cut the desired length of thread or been retracted the desired distance.

Now, referring more particularly to Figs. 5 to 9 inclusive, details of a preferred form of threading shift lever will be described.

The lever 65 is pivotally mounted on a pin 68, supported by a part 69 of the frame of the machine. The lever is provided with a yoke 70, having means for engaging the spool 64, whereby the latter may be shifted to engage either the clutch 60 or the clutch 62. In the particular arrangement shown, the shaft 42 loosely extends through an enlarged passage 71 in the lever. The upper end of the lever is provided with a cam roll 72, which, in the preferred form illustrated, is movably connected to the lever, as by means of a dovetail connection 73, permitting transverse sliding of the cam follower 72 on the lever. Any suitable means, such as a screw 74, serves to limit the extent of movement of the cam roll 72 on the lever. The lower portion of the slide 75 which carries the cam roll 72 is provided with means, such as teeth or projections 76-77, for alternate engagement with teeth or pawls 78-79 carried upon what may be termed an escapement lever 80. The escapement lever 80 may be pivotally mounted on the lever 65 by a pin 81. Any suitable type of friction device 82 may be provided for frictionally holding the escapement lever in different positions. The pivotal movement of the escapement on the clutch lever 65 is limited, as by means of a pin and slot connection 83, for a purpose to be described.

For the purpose of moving the escapement and throwing the lever 65 to neutral position at the end limit of the running on or running off movement of the threading tool I may employ

means actuated by the threading spindle. In the form shown I employ a rod member 84, slidably mounted on the head stock portion of the frame and carrying a fixed collar 85, which may be engaged by a sleeve or collar member 50, normally movable longitudinally with the spindle. This collar member 50 may carry the cam roll 51 (see Fig. 4) when the No. 4 spindle is used for ordinary forming operations other than threading. The rod 84 is provided with an abutment member, which may be in the form of a collar or yoke 87, which may be slidably mounted upon the rod 84. In the form shown the yoke collar has a stop pin 88 therein, which passes through slots 89-89 in the tubular rod 84, so as to permit sliding movement of the abutment collar 87 on the rod 84, for a purpose to be described. The tubular rod 84 carries means, such as stop rods 90-91, which alternately abut the stop pin 88 on the abutment collar 87 upon movement of the rod 84 with the threading spindle. The stop rods 90-91 may be held in various positions of adjustment in the rod 84, as by means of threaded adjusting screws 92-93 at opposite ends thereof. The abutment yoke collar 87 has abutment surfaces 94-95 at spaced points, thus forming a yoke extending over the lower end of the escapement lever 80, so that, upon movement of the yoke collar 87, the escapement lever may be shifted by the engagement therewith and movement of either of the abutment surfaces 94-95.

The threading clutch shift lever operation is as follows:

Assume the shift lever 65 to be in the neutral position, as shown in Fig. 9, and the escapement 80 tilted so that the parts 76-78 are in engagement with each other. The cam 66 (Fig. 5) on the cam drum 48 engages the cam roll 72 on the lever slide 75 and moves the same toward the left. Movement of the roll 72 toward the left as viewed in Fig. 9 will, acting through the inter-engaged parts 76-78 and the connection of the escapement lever 80 to the shift lever 65, rock the latter in a counterclockwise direction, to engage the right hand clutch 60, so as to clutch the gear 38 to the threading clutch shaft 39. With the gear connections as shown in full lines in Fig. 5, the threading spindle will then be rotated for running on right hand threading. The threading spindle is moved forward relatively to the work opposite the threading tool by any suitable means, such as the cam 67 (Fig. 5) or thread leader mechanism. When a thread of the requisite depth has been cut, the push rod 90, movable with the rod 84, which is in turn carried along with the threading spindle in its forward movement, engages the stop pin 88 carried on the abutment yoke collar 87, and shifts the same toward the right as viewed in Figs. 8 and 9. The push rod 90, engaging the stop pin 88, carries the collar 87, together with the abutment surface 94, toward the right, so as to rock the escapement lever 80 from the position shown in Figs. 8 and 9 into the opposite position (shown in Fig. 7). This rocking movement is limited by the pin and slot connection 83, and further right hand movement of the push rod 90, acting through the stop pin 88, collar 87 and abutment surface 94 engaging the side of the lever 80, moves the shift lever 65 so as to rock the latter in a clockwise direction about its main pivot 68, so as to throw the clutch spool 64 into the neutral posi-

tion. The parts will now be positioned substantially as shown in Fig. 7. Since the forward threading clutch 60 has been thrown out, the threading spindle will stop. If any adjustment 5 of the length of thread being cut is desired, the cam drums controlling the feed functions of the machine may be stopped by means hereinafter to be described, and the position of the stop 92 is adjusted, so as to permit the making of a 10 longer or shorter thread, as may be required.

With the cam drum 48 continuing its rotation another cam (not shown) similar to cam 66 but acting in the opposite direction, engages the cam roller 72 and moves the latter toward the right 15 as viewed in Fig. 7. It will be noted that the previous rocking of the escapement lever 80 has shifted the teeth 77-79 into engagement with each other, so that continued movement of the cam roller 72 toward the right, acting 20 through the escapement lever 80 and its connection 81 to the clutch lever 65, rotates the latter in a clockwise direction, so as to move the cam spool 64 to engage the clutch 62 and clutch the reverse threading gear 61 to the shaft 39, 25 which, through the gearing hereinbefore described, causes the running off rotation of the threading lever and the threading spindle is retracted by thread leader mechanism or by the threading tool running out of the cut thread or 30 by other means, as may be desired. When the requisite retractive movement of the threading spindle has been effected, the push rod 91 engages the abutment pin 88 and moves the same toward the left. This movement of the abutment pin 88 causes the escapement 80 to rock 35 from the position shown in Fig. 7 to that shown in Figs. 8 and 9, and further movement of collar 87 and its now active abutment surface 95 again throws the lever 65 into neutral position, as 40 shown in Fig. 7, after the manner hereinbefore described. The reverse threading gear 61 is thus unclutched from the shaft 39 and the threading spindle ceases to rotate until the cam 66 again throws the lever 65, to begin another 45 cycle of operations like that heretofore described.

The particular utility in having the cam roll 72 movable relatively to the lever is for the sake of safety. It is quite possible that one of the 50 cams, as 66, after engaging the cam roll 72 and throwing the clutch shift lever 65 so as to cause either the gear 38 or 61 to be clutched to the shaft 39, may still be in contact with the cam roll 72, when the machine attendant, for some 55 reason, throws out a clutch and stops the further rotation of the cam drum 48 and other feed control means. It will be plain that, with the cam roller 72 in engagement with a cam, as 66, which has been stopped, it would be impossible 60 to throw the clutch shift lever 65 into neutral position if the roller 72 were rigidly fixed to the lever 65, and unless the lever 65 can again be thrown into neutral the threading spindle would continue to rotate and continue 65 to feed, with great danger of breaking parts of the machine. It will be plain that, with the escapement lever 80 in the position shown in Figs. 5 and 8, when the threading spindle moves in the threading direction, that is, to the right, 70 sufficiently far for the push pin 90 to engage the stop pin 88, the escapement 80 will be rocked out of the position shown in Fig. 8 and into the position as shown in Fig. 7, and the parts 76-78 being then out of engagement with each 75 other will permit the lever 65 to be thrown from

the clutched position shown in Fig. 8 to the neutral position shown in Fig. 7. During this throwing of the lever 65 by the push rod 90, the cam roller 72 may remain substantially stationary in contact with a cam, such as 66, 80 while the lever oscillates and slides over the cam roll slide 75. During the normal operation of the machine, when a cam, such as 66, is not stopped while in engagement with the cam roll 72, the latter, together with its slide 75, does not slide relatively to the lever 65 but remains in substantially the same position and is held against movement by the escapement teeth 76-78 or 77-79, depending upon the position of the escapement 80. By means of the releasable connection between the lever 65 and the cam roll 72, it will be impossible for the threading lever to continue a threading or unthreading movement further than the predetermined 95 distance, as determined by the push rods 90-91, held in adjusted positions, as by means of adjusting screws 92-93.

Double threading

It is often desirable in threading operations 100 to provide positive thread leader mechanism. I have devised novel thread leader mechanism, which will be described. I have also devised mechanism for performing a double threading 105 operation. It is sometimes desirable to provide concentric threading spindles carrying a tap and die, and each fed forwardly independently of the other, but preferably both rotating together. My novel double feed mechanism may be provided 110 as an attachment to the machine, which may be omitted from the machine when not required, or attached to existing machines having the proper concentric spindles.

In Figs. 10, 11 and 12 I have disclosed a preferred embodiment of a double threading attachment, certain features of which are of utility 115 when only a single thread is to be cut. My improved double threading attachment may include a base frame 100, which may be attached 120 to a part of the frame by any suitable means. The No. 4 or threading spindle, as herein shown, includes an outer tubular spindle 101 and an inner spindle 102 splined to the tubular spindle, so as to cause both to rotate together 125 but yet permit independent feeding of the two spindles. The frame 100 is provided with a thread leader member, such as a leader nut 103, while one of the spindles, such as the inner spindle 102, is provided with a complementary 130 thread leader member, such as a leader screw 104. The spindle 101 has splines 105 formed thereon, and the leader nut 104 is correspondingly formed, so as to be rotatable with but 135 slidable on the spindle 101. Suitable keying means, such as a key 106, may extend through a slot in the leader screw 104 and through an elongated slot 107 in the spindle 101. This key 106 engages the inner spindle 102 or an adjustable extension 108 thereon. Suitable locking means, such as a screw 109, secures the key in place. Now, upon rotation of the spindle 101 and consequently rotation of the inner spindle 102, the leader screw 104, by reason of its engagement with the leader nut 103 fixedly held 145 in the frame or casing 100 by any suitable means, will cause the inner spindle 102 to be fed forwardly or rearwardly, depending upon the direction of rotation.

In order to feed the outer spindle 101 I pro- 150

vide thread leader mechanism, one member of which, such as the leader nut 110, is fixedly secured in the frame or casing 100 and is preferably out of alinement with the first leader nut 103. A coacting leader member, such as a leader screw 111, cooperates with the leader nut 110 to feed the outer spindle 101. The leader member 111 and the outer spindle 101 may be geared together, so as to cause the proper rotation of the leader 111 and feed of the spindle. In the form shown I provide a gear casing 112, carrying a spur gear 113, definitely fixed against axial movement therein. The gear 113 is rigidly secured to the leader screw 111. A second gear 114, meshing with the gear 113, is likewise secured within the casing 112, against axial movement therein. The gear 114 is secured against rotation on the spindle 101 by the splines 105 and may be definitely held against axial movement in one direction on the spindle 101, as by means of a split thrust collar 115, which may fit in a groove formed circumferentially of the spindle 101. The gear 114 is held at the opposite end by suitable means, such as a nut 116. The gear casing 112 is slidably connected to the frame or casing 100 by suitable guideway means. In the form shown, the casing 100 carries a wedge slide member 117, while the gear casing 112 is carried upon a slide portion 118, having ways fitting the slide 117 and providing a dovetail connection for definitely holding the main frame and casing in definitely aligned slideable relation to each other. It will be plain that, upon rotation of the spindle 101, the gear 114 carried thereby will be rotated and, since gear 113 is in mesh with gear 114, the gear 113, together with leader screw 111, will be rotated in a direction opposite to the direction of rotation of the spindle 101. Therefore, the thread on the thread leader 111 should be a left hand thread when it is desired to feed the spindle 101 for right hand threading. It will be obvious that by interposing an idler between the gears 113 and 114, a right hand thread could be employed on the leader screw 111.

With gears 113—114 of the same size, the outer spindle will be fed at the rate determined by the lead of the thread on the screw 111. It will also be noted that, with the same leader members 110—111, the spindle 101 may be fed at different rates, depending upon the proportioning of the gears 113—114. Thus, by removing the gears 113—114 and substituting other gears, threads of different pitch may readily be cut, without changing the leaders 110—111.

It will thus be clear that with the two sets of thread leaders in engagement with each other, rotation of the spindles 101—102 will cause rotation of the leader members 104 and 111, and consequently a feed of the respective spindles at the rates determined by the thread leader members or the gearing 113—114. Thus, threads of different pitch may be simultaneously formed on an article held in a suitable chuck.

65 Cam drive

The feed mechanism may be actuated by a chain concealed by a chain guard 120 (Figs. 1 and 2) and trained over sprockets 121—122 (Figs. 5 and 14). The drive mechanism preferably includes a slow traverse device for use during forming operations and a "hurry up" mechanism or fast traverse for rotating the cam drums during the remainder of a cycle of operations.

Referring more particularly now to Figs. 14, 15, 4 and 3, it will be seen that the sprocket 122 drives a shaft 123 carrying a spur gear 124 thereon. The gear 124 meshes with and drives a spur gear 125, partly shown in Fig. 14 and concealed in rear of the gear 124 in Fig. 15, which gear 125 is mounted upon a shaft 126 of the slow traverse. A pinion 127 on shaft 126 drives a gear 128 on a sleeve which carries a second gear 129. The gear 129 meshes with a gear 130 carried upon a sleeve on shaft 126, which sleeve also carries a gear 131. The gear 131 drives a gear 132 carried by one part of a ratchet mechanism or overrunning clutch 133, which may be of conventional form. The other part of the overrunning clutch is connected to a shaft 134 for driving the same and the cam mechanism, as will be later described. The gears just described in the housing 135 may be change gears, so as to permit ready variation of the slow traverse speed of the shaft 134.

The gear 125, driven by the gear 124, meshes with the gear 136 carried upon a part of the clutch 137 on shaft 134. The gearing is so proportioned that when the clutch 137 is thrown in, the drive will be from gear 124 to gear 125 to gear 136, and the speed of the shaft 134 will be higher than when the drive goes through the gearing in casing 135 and overrunning clutch heretofore described. During the fast traverse, that is, when the clutch 137 is thrown in, the overrunning clutch is permitted to rotate and the shaft 134 merely runs ahead of the driving part of the overrunning clutch 133, driven by the slow traverse gearing in casing 135. The clutch 137 is normally actuated by means of the cam roller 138 on the lever 139, which moves the clutch cone 140. The cam roller 138 is moved by means of a cam (not shown) on the cam spool 139a (Fig. 14) and timed to throw in 115 the fast traverse during indexing and idle movement of the machine.

The shaft 134 carries a clutch part 141, which is controlled by a cone 142, movable manually by the yoke 143 and operating lever 6 on shaft 144 120 (Figs. 1 and 4). Upon throwing in of the clutch cone 142 the shaft 134 is clutched to the shaft carrying driving pinion 145, which ultimately drives the cams. Thus, by throwing out the clutch 141—142, the feed functions of the machine may 125 be stopped, while the gearing heretofore described may continue to rotate. Upon further reference to Figs. 14, 15 and 4 it will be seen that the pinion 145 drives spur gear 146, which carries with it a pinion 147, which in turn drives the gear 148 carried by the stub shaft 149. The stub shaft 149 also carries a pinion 150 which meshes with the spur gear 153 on cam shaft 154 (for indexing and for moving cam spool 139a). An idler gear 151 meshes with the driving gear 153 and with cam drum drive gear 152 connected to cam drum 47. An idler gear 155 on stub shaft 156 meshes with drive gear 153 and with cam drum gear 157, which drives cam 140 drum 48.

Turret indexing

Referring particularly to Figs. 16 and 18 it will be seen that the frame of the machine is 145 provided with a bearing 160 for receiving the large extended bearing surface 161 of the turret. A clamping cap 162 serves to complete the bearing and forms a means for rigidly clamping the turret in longitudinally adjusted and indexed 150

- positions. The bearing portion of the turret is provided with a plurality of locking slots 163—163, equal in number to the number of indexed positions of the turret. A locking bolt 164, preferably wedge-shaped at one side to coact with the correspondingly shaped locking slots 163, is movable into locking engagement with the slots 163, preferably by spring means (not shown), which may be conventional, and is moved to the 10 unlocked position by means of a lever 165, pivoted at 166 to the frame of the machine and actuated by a cam roll 167, engaged by a cam 168 upon the cam shaft 154 extending longitudinally of the machine.
- 15 The turret clamping cap 162 is preferably spring pressed into closed or locking position and is opened by cam means against the pressure of such spring means. In the form shown I provide a clamping cap draw-rod 169, secured to 20 the clamping cap and extending down within the base of the machine. A clamping cam lever 170 may be pivoted at 171 to a fixed sleeve member 172 carried by the frame, and a swivel pin, the end of which is indicated at 173, may serve to 25 secure the draw rod 169 to the yoke of the lever 170. One arm of the lever 170 is pivotally connected to a tension rod 174, which extends to the outside of the machine and is urged in one direction, as by means of a spring 175, so that the 30 spring, in drawing upon the rod 174, constantly tends to rock the lever 170 about the pivot 171 and draw the clamping draw-rod 169 down into clamping position. An adjusting sleeve carrying abutment 176 and spring 175 and accessible from 35 the outside of the machine, is provided for adjusting the force exerted by the spring 175. Another arm of the lever 170 carries a cam roller 177, which is engaged by a cam 178 on the cam shaft 154, so that, upon engagement of the cam 40 178 with the cam roller 177, the spring 175 is compressed, the lever 170 rocked about the pivot 171, and the rod 169 thus released, after which the spring 179 may assist in loosening the clamping cap 162, to permit the turret to be 45 indexed. The positioning of the cams 168—178 is such that the locking bolt 164 is retracted and the clamping cap 162 released before the indexing movement of the turret is started and the locking bolt moved into locking position to 50 definitely position the turret before the clamping cap is permitted to clamp the turret in such definitely located position.
- The indexing of the turret is preferably effected by a Geneva motion. In the form shown 55 a star wheel 180, having radial slots 181—181 therein, is fixedly secured to the turret, so as to be capable of rotating the latter upon rotation of the star wheel. An actuating arm 182, carrying a roller 183 for coaction with the slots 60 181, to form the Geneva motion, may be slidably mounted upon a bar 184 fastened in headstock 2. The star wheel 180 and actuating arm 182 are constrained to move together by suitable means, such as a peripheral flange 185 on 65 the star wheel engaging in a circumferential groove 186 in the necked portion of arm 182 connecting it with a gear 187. The gear 187 meshes with a gear 188 on the cam shaft 154. These gears are shown as round spur gears, but may 70 be eccentrically mounted gears if desired, to give a variable motion to the actuating arm 182, for the purpose of modifying the action of the Geneva motion, if that be found desirable. Since 75 the star wheel 180 moves longitudinally with the turret to its various positions of adjustment,

the actuating arm being constrained to similarly move, I make one of the engaging gears 187—188 relatively long, so that these gears will always remain in mesh between the limits of longitudinal adjustment of the turret. 80

Forward turret support

As will be clear from Figs. 16 and 18, the turret has an extended bearing in the frame of the machine in rear of the chucks. In addition to this extended rear bearing I prefer to provide a forward bearing for the turret. In the form shown the turret proper has a long forward extension 190 (Figs. 1, 16), which may be integral with the turret, and extends into a bearing 191 (Fig. 5) in the head stock end of the machine. This forward extension on the turret bearing directly in the head stock serves to assist in aligning the turret with the head stock, avoids an overhang of the forward end of turret and chucks and thus insures greater accuracy in the work turned out by the machine. 85 90 95

In lieu of or in addition to the clamping cap 162 heretofore described, I may employ additional means for resisting the tool thrusts while 100 the machine is in operation. I preferably secure abutment means to the forward extension 190 on the turret and position such abutment means on that portion of the head stock which receives the cam thrusts occasioned by the feed- 105 ing of the tools and work relatively to each other. In the form shown the forward extension 190 is provided with a plug 192 fixed thereto and having a receiving pocket for an anti-friction bearing 193, which may be held in place 110 by a gland 194. A tension member 195, having a head 196 behind the antifriction bearing 193, extends through the head stock and is secured therein. As shown in the illustrative example 115 herein, the head stock is bored and counterbored for receiving the sleeve 197 (which also forms a bearing for the gear 13). The tension member 195 passes through the gland 194 and the threaded end thereof may be engaged by a long nut 198, which may carry a micrometer dial 199 120 and spanner nuts or similar devices 200, for rotating the long nut 198 and thus positioning the tension member 195 in the head stock. A gland 201 may serve to position the nut 198 relatively to the sleeve 197. 125

Thus, the collective tool thrusts are taken at least in part by the forward turret extension 190, tension member 195 and nut 198, bearing directly upon that part of the head stock which takes the oppositely acting cam thrusts. The 130 turret clamping cap is thus assisted in maintaining the turret and head stock in definitely spaced relation during the operation of the machine. By rigidly holding the turret and head stock relatively to each other inaccuracies in 135 facing or other cuts may be practically eliminated. By means of the micrometer dial 199 nice adjustments of the turret may be indicated.

Fluid chucking

140

The turret, in the present form of machine, is equipped with a plurality of chucks, which may be operated either manually or otherwise. In the preferred form illustrated I employ fluid pressure chucking mechanism which may be operated by any fluid, such as air, or a liquid, such as oil. The particular embodiment illustrated is designed for hydraulic chucking.

Now, referring particularly to Figs. 16, 17, 19 to 26 inclusive, it will be seen that I have pro- 150

- vided a plurality of cylinders 205, one for each chuck. In the form shown, wherein the tools, instead of the chucks and cylinders, rotate, these cylinders are in a single block, which may be 5 secured to the turret in any suitable manner. The block as herein illustratively shown is secured to a flange 206 forming the tail end cylinder heads. An extension 207 on the flange 206 is rigidly secured in a bore of the turret proper 10 by any suitable means (not shown). In the present particular embodiment the star wheel 180 has been secured on the tubular extension 207, so that the turret, star wheel and cylinders all move with the turret. Each cylinder is 15 provided with a piston 208, and a piston rod 209 extends from each piston through the tail end cylinder head to a chuck. The valves, to be hereinafter described, are preferably arranged so that pressure acting on the larger or head 20 end of the piston is employed for chucking, while the drawback or unchucking movement is caused by the pressure acting upon the tail end of the piston. Due to the reduction of piston area by the piston rod, this drawback pressure is less 25 than the forward or chucking pressure.
- The head end cylinder heads, for the sake of convenience in manufacture, are preferably formed by a plate 210, extending over the head ends of the cylinders and fluid passage blocks or 30 heads 211 secured directly to the cylinders. The fluid passage blocks 211, whether made as individual blocks or as one integral head, are preferably cored out, as shown more particularly in Fig. 22, for the purpose of providing the requisite fluid passages. The end plate or part of 35 the cylinder head 210 is provided with passages registering with those of fluid passage blocks 211, for the purpose of conducting fluid to and from the opposite ends of each cylinder.
- 40 Pressure fluid may be conducted to and from the fluid passage blocks 211 by mechanism shown more particularly in Figs. 16, 17, 20 and 24. That construction includes a shaft-like member 212, rigidly secured in a central bore 213 in the 45 cylinder block. This shaft-like member is provided with longitudinal passages 214-214, which serve as inlet passages, and with corresponding passages 215-215, which constitute the exhaust passages. The shaft-like member 212 may be provided with a cored annular collar 216 rotatably mounted on the shaft member 212 and held between stuffing boxes 217-217. Between the annular collar 216 and the shaft member 212 is an annular passage 218 for receiving pressure fluid through the inlet pipe 219. A suitable bore connects the annular pressure space 218 with each of the longitudinal bores 214-214 in the shaft member 212 as will be understood. Each bore 214 at the inner end is connected by 55 a port or ports 220 with an annular space 221 between the cylinder block and the shaft member 212. A second annular cored collar 222 is rotatably held on the shaft 212 between the stuffing box 217 and an outer stuffing box 223.
- 60 An annular space 224 is formed between the collar 222 and the shaft 212. Suitable ports connect the space 224 with the exhaust passages 215-215 in the shaft 212. The inner ends of the passages 215-215 are in open communication with an annular space 225 between the cylinder block and the shaft 212, so that such annular space 225 constitutes the exhaust passage. Thus, the annular inlet space 221 and the 70 annular exhaust space 225 will be in constant communication, respectively, with the pressure inlet pipe 219 and the pressure exhaust pipe 226. By collecting the exhaust pressure fluid from all of the cylinders, as at 226 near the inlet pipe 219, it is possible to readily reverse the pressure connection 219 and exhaust connection 226 so as to reverse the action of the pistons upon the same movement of the control valve to be described. This ready reversal is of importance when one type of chuck requiring a rearward piston movement for gripping is substituted for one requiring a forward piston movement for gripping.
- 75 As may be clearly seen in Figs. 17 and 24, the annular inlet pressure space 221 is connected to each of the cylinders 205 by a passage 227, and each cylinder is connected to the exhaust space 225 by a passage 228. Each passage 227, extending through the cylinder head portion 210, connects to a pressure passage 229 in the fluid passage block 211, as will be clearly seen from Fig. 22. Each exhaust passage 228 is in open communication with an exhaust passage 230 in the fluid passage block 211. A passage 231 in the block 211 is connected directly to the head end of each cylinder. A passage 232 in the block 211 connects to a passage 233 extending to and in communication with the tail end of each cylinder. Extending through from the rear passage side to the forward valve side of each passage block 211 is a port 234 (Figs. 20 and 22), connecting to the pressure passage 229, a passage 235 connecting to the exhaust passage 230, a passage 236 connected to the head end of each cylinder, and a fourth passage 237 connected to the tail end of each cylinder.
- 80 A simple type of cup valve (shown more particularly in Fig. 23) may serve to control the flow of fluid to and from the ends of the cylinder. Such a valve may include an annular cup 238, having a transverse partition 239, providing two 85 fluid passages 240-240 at opposite sides of such partition. Each valve fits over the passages 234-235, 236-237 and may be held in position, as by means of a spring 241 secured by a valve bonnet 242. Each valve may be actuated by 90 means of a stem 243, which has a squared portion fitting a square hole in valve and provided with an arm 244, which may carry a cam roller 95 245 for actuation by a cam.
- 95 With the valves positioned as shown in Fig. 125 20, fluid pressure will be conducted to the head end of each cylinder except the one in the upper left hand position of Fig. 20. The tail end of each cylinder except the upper left hand one will be connected to exhaust. These are the normal 100 130 positions of four of the valves during the time that the chucks are automatically held closed and operations are being performed on work pieces. As each cylinder reaches the position corresponding to the upper left hand position 135 of Fig. 20, the valve is thrown so as to conduct pressure fluid to the tail end of each cylinder and exhaust fluid from the head end, so that a chuck will be opened for reloading.
- 100 I have devised improved actuating means for 140 the valves. Since it is desirable to maintain the valves in position so as to maintain fluid pressure on that end of the piston acting in the chuck closing direction (in this case the head end), I provide a concentric cam track, designated generally 250, for holding each of the valve arms 244 in definite position, except that valve arm which is in the loading position of the chuck. Such cam track may be formed of a 145 stationary cam part 251, held to the frame of 150

the machine in any suitable manner (not shown). In the specific illustration there is a sleeve extension 252 fitting over the fluid passage shaft member 212 (Fig. 16). The surface 253 forms one of the concentric cam surfaces, while one or more peripheral, circular cam track members 254 may be detachably secured to the cam body 251, as by means of screws 255. The cam plates 254 are preferably made detachable, so that in case it becomes desirable at any time to throw a valve in a position other than the normal loading position thereof, the appropriate cam track portion 254 may be removed and the valve thrown manually.

For the purpose of throwing the valve in the loading position or when it is desired to actuate such valve automatically as it approaches the loading position, I provide another cam portion for that purpose. In the preferred form illustrated such cam portion, preferably of V-form 256, may be mounted upon a slide 257 and moved manually through a link 258 actuated by means of a lever 259, and ultimately thrown by rocking movement of the hand lever 7 (Fig. 1) herefore mentioned. This slide 257, when depressed, occupies the position substantially as shown in Fig. 26, and the upper part of the V-shaped cam surface 256 is about flush with the concentric surface 253 on the stationary cam part 251. By raising the slide 257 the valve cam roller shown in dot and dash lines in Fig. 26 will be elevated to the position shown in Fig. 25, and that particular valve will then be in the relative position shown for the upper left hand valve of Figs. 19 and 20. This is the position of the valve for exhausting pressure fluid from the head end of the cylinder and admitting pressure fluid to the tail end, for opening a chuck. When a work piece has been removed from the chuck in the loading position and a new work piece inserted, either manually or automatically, the slide 257 may again be depressed by actuation of the hand lever 7 (Fig. 1), and consequent actuation of the lever 259 and link 258, so that the slide will occupy the position of Fig. 26 and the valve will again be thrown to the chuck closing position and the chuck will then be closed.

In order to obviate the possibility of open chuck jaws colliding with tools during indexing movements of the turret, I provide means for automatically throwing each valve to the chuck closing position, in case the machine attendant fails to throw the valve manually, as heretofore described. Such a safety device may be in the form of an inverted V cam portion 260, formed integrally with or secured to the main cam body 251. The ends of this V closing cam surface preferably merge into the concentric portion of the cam surface, as shown more particularly in Fig. 19. Thus, if the valve be not thrown manually by depressing the slide and causing the cam surface 260 (Figs. 25, 26) to return the valve to the chuck closing position, the roller will be automatically cammed down into the chuck closing position shown for the four lower valves of Fig. 19. If the valve slide 257 be permitted to remain in elevated position, each valve roller 245 would automatically ride up on the V cam surface 260, and each valve be automatically thrown so as to open a chuck. Each valve, as heretofore described, would also, through the cam surface 260, be automatically closed before reaching the next indexed position of the turret. Since each cylinder and its valve and other connections are preferably duplicates

of every other, it will be clear that, as each chuck reaches the loading position, it may be either manually or automatically opened, and the finished work piece removed, a new work piece inserted and the chuck either manually or automatically closed again, so that the work piece will be chucked when it reaches the next indexed position of the turret.

Fluid pumps

As stated, chucks may be actuated either manually or by fluid pressure means. When actuated hydraulically, as by oil pressure, I prefer to provide a pump and drive the same directly from a source of power actuating other portions of the machine. As shown more particularly in Figs. 28 and 29, I may provide a fluid pressure pump 270 for chuck actuating pressure fluid and may also employ a second pump 271 as a coolant pump. The drive for both pumps may be from a gear 272 on the head stock portion of the machine through a chain 273 concealed by the chain guard 274 (Fig. 2) and driving a sprocket 275 (Fig. 29). The sprocket drives a shaft 276, carrying at its opposite end a spur gear 277, which drives an internal gear 278, which in turn drives a spur gear 279, which meshes with a gear 280, driving the shaft of a lubricator. The shaft 281 carrying the annular gear drives a spur gear 282, which in turn drives the spur gear 283 for driving the pumps 270-271.

The chucking fluid pump 270 draws liquid through the suction pipe 284 in a reservoir compartment 285 and discharges fluid through the pipe 286. Excess fluid is conducted through a by-pass or pressure relief 287 and through the pipe 288 back to the suction compartment 285. Between the pump 270 and the pressure relief or by-pass valve 287 I may provide a comparatively large air bell 286' which may act as a storage reservoir and in effect an accumulator to store up liquid under pressure which will be available for chuck actuation when required. With such accumulator the shock of pump pulsation will not be felt on the pressure relief valve. The pressure fluid required is conducted through the pipe 219, which ultimately reaches the distributing mechanism, shown more particularly in Fig. 16. The discharge pipe 226 of Fig. 16 returns exhaust fluid to the fluid compartment 285.

The coolant pump 271 draws coolant through the suction pipe 289 and conducts the same through pipe 290 to the tools. There is, as usual, a chip separator (not shown), for separating the chips from the coolant and permitting the coolant to fall back into the coolant reservoir 291, to be again sucked up in the pipe 289. I prefer to make the pressure fluid reservoir 285 and the coolant compartment 291 as a single integral reservoir, divided by a partition 292. This divided reservoir is preferably concealed within the base of the machine.

Chucks

Chucks of various kinds may be advantageously employed with my machine. In Figs. 31, 32 and 33 I have illustrated two-jaw screw chucks, and in Figs. 34, 35 and 36 are illustrated three-jaw collet chucks.

The screw chucks illustrated in Figs. 31, 32 and 33 may comprise jaws 300-300, actuated as by means of a right and left hand screw 301, which may itself be actuated manually by means of an appropriate wrench applied to the angular head

302 on the screw 301. For fluid pressure chucking I prefer to actuate the jaws by means of rack and pinion means. In the form shown the screw 301 is provided with an elliptical gear 303, 5 meshing with a second elliptical gear 304 carried on a transverse shaft 305, which also carries a pinion 306. A rack 307, indicated in dot and dash lines in Fig. 32, (since the rack is in the foreground) meshes with the upper side of the 10 pinion 306. Now, upon application of fluid pressure to the head end of the pistons shown more particularly in Fig. 16, the rack engaging the pinion 306 will rotate the elliptical gears, and consequently the right and left hand screw 301, 15 and cause the jaws to close. The elliptical gears are preferably so positioned that a greater force may be exerted by the jaws when in the normally closed position than when in the normally open position. Each rack 307 is preferably 20 housed within the body of the chuck, so that it will not project therefrom and will always be housed so as to prevent the entry of chips or other foreign matter.

Without any changes in fluid actuated means 25 I may also employ collet chucks, as shown in Figs. 34, 35, 36. In the collet chucks there shown the chuck jaws 310—310 are closed by drawing back on the draw rod 311. The latter is preferably actuated by the rack. In order to 30 permit of such actuation, I preferably employ a transverse shaft 312 in the chuck body and secure an eccentric 313 thereon, which fits within an elongated slot 314 in the draw rod 311. A pinion 315 meshes with the rack 307 which, in 35 this instance, also is snugly housed within the chuck body, and forward movement of the rack rotates the pinion and eccentric into the position substantially as shown in Fig. 36, which is the closed position of the collet chuck. Rearward movement of the rack 307 rotates the eccentric oppositely so as to cause the jaws to be 40 opened.

It will be observed that, with the rack and pinion and eccentric actuation of the chuck jaws, 45 a uniform force acting on the rack will transmit a variable force to the drawback rod 311 and, when the eccentric is in the locking position as shown in Fig. 36, the greatest closing force will be exerted upon the chuck jaws and, if the eccentric be substantially on dead center, such 50 positioning will serve in a measure as a lock for holding the jaws closed, regardless of whether or not the same pressure is always maintained on the fluid actuated piston.

55 General operation

Assume that the various gears and cams have been determined and set for the proper feeds and speeds for the particular operations to be 20 performed by the machine. This preliminary set up may be facilitated by use of the hand cranking device including shaft 320 and meshing bevel gears 321 (Figs. 4, 15). The motor is started and through the gearing (Figs. 3, 4 25 and 5) the spindles are set in rotation. The lever 7, at the machine attendant's right (Fig. 1) may be rocked outwardly so as to throw a valve to open the chuck in the loading position (Fig. 19). After a work piece has been inserted in 30 the chuck, the lever 7 is rocked inwardly and, through the splined connection 325, the valve slide (Fig. 19) is lowered so as to close the chuck in the loading position. If the No. 0 spindle is equipped with a manual feed device (Fig. 5 35 13), the manual lever (Figs. 1 and 13) may be

moved to perform a drilling, reaming or other operation on the work piece held in the chuck in the loading position. After retracting the tool by the manual lever 53, the feed works may be thrown in, either by moving the lever 6 (Fig. 83 1) to the right manually, or by moving the lever 7 at the operator's right toward the right, which lever 7, acting through the connecting rod and rotatable connection 326, throws in the clutch 143 (Fig. 15), to start the feed works. The 85 turret then indexes and brings another chuck to the loading position for operator to load, and the tools are advanced toward the work pieces held in the chucks, and, after the appropriate operations have been performed at the various stations, the tools are retracted and the turret again indexes, to bring another chuck to the loading position and when the machine is operating normally a finished piece is brought to the loading station each time the turret indexes. 90 The lever 7 may be moved outwardly to unchuck the finished work piece at the loading station. A new work piece is then inserted, the lever 7 moved inwardly to chuck such new work piece, and the turret again indexes. 95

It will be seen that the operator, by keeping his hand on the lever 7, may open and close chucks and start or stop the feed works, all with one hand and with the single hand lever 7. Normally, the feed works may operate continuously, and it is only when an unusual length of time is required in the loading station that the feed works would be thrown out during the operation of the machine. 105

As has been described in detail in connection 110 with threading, the threading tool may thread into the predetermined desired extent, after which the threading clutch lever (Figs. 5 to 9) is thrown out, so as to stop the threading spindle. Immediately or any time thereafter, the 115 reverse threading clutch may be thrown in by cam means. If, while the threading clutch lever cam roll is in engagement with a cam and the feed works be thrown out, the threading tool will move inwardly or outwardly, as the 120 case may be, only to the predetermined desired extent, determined by the adjusting screws 92—93 (Fig. 5), after which the threading clutch lever is thrown to neutral, regardless of whether or not the threading clutch lever cam roll is in 125 engagement with a cam.

The fast and slow traverse (Figs. 14 and 15) are set so that ordinarily the slow traverse will be employed during the time that the tools and work pieces are in engagement with each other, 130 and the fast traverse is employed for the drawbacks, indexing and jumps of the tools. 135

The chucking and unchucking of the work pieces may be performed automatically merely by keeping the hand lever 7 drawn outwardly, but ordinarily and for relatively heavy work pieces, for which this machine is particularly 140 designed, manual actuation of the lever 7 for chucking and unchucking is preferable for each work piece, loaded or unloaded. The location 145 of the chuck control hand member 7 on the frame in a position forwardly of the cylinders and toward the chucks within convenient reach of an operator in front of the chucks is of great advantage in facilitating loading. Such location of the handle 7 furthermore permits the ultimate pressure control or valve means to be located at or near the cylinders and avoids long pressure conduits and otherwise makes for simplicity and compactness. 150

During the operation of the machine the turret and head stock are maintained in accurate alignment not only by means of the bed of the machines and the clamping of the turret, but by the forward extension 190 (Figs. 5 and 16), so that not only is accuracy assured, but the combined tool pressures are partly taken by the forward extension 190 and its thrust bearing in the head stock on the same portion of the latter, against which the cam thrusts come.

The chucks may, of course, be of any desired form, but with chucks as herein disclosed a uniform thrust or pull of the fluid actuated means transmits a variable force to the chuck jaws, so that heavy chucking pressure will be effected without correspondingly large pistons. With the eccentric-operated type of chuck shown in Figs. 34, 35, 36, the chucks are in a measure self-locking and the jaws grip the work pieces rigidly, even though there might be a loss of pressure in the fluid actuated means, tending to close the chuck jaws.

It will be seen that I have improved various mechanical and functional features in a machine of the character indicated, tending toward facility of operation, speed and accuracy. Not all of the features herein disclosed need be used simultaneously, since various features are of utility not only in machines of the present type, but also in machines of other types.

A preferred embodiment of the machine has been described in great detail, but I do not wish to be limited to the particular embodiment shown, since many changes, omissions and additions may be made within the scope of the invention as defined in the appended claims.

I claim:

1. In a machine of the character indicated, a threading spindle, a pair of clutch gears for driving said spindle in the forward and reverse directions, means for driving one of said clutch gears always at a higher rate than the other of said clutch gears, and means for reversing the rotative directions of said clutch gears whereby the high speed clutch gear may always be used for unthreading and the low speed clutch gear for threading.

2. In a machine of the character indicated, a threading spindle, a forward feed clutch, a reverse feed clutch, means for rotating said forward feed clutch at a lower speed than the speed of said reverse feed clutch, and means for reversing the direction of rotation of said forward and reverse feed clutches, for the purpose described.

3. In a machine of the character indicated, a threading spindle, a forward threading clutch, means for operating the same in one direction at a low speed, a reverse threading clutch and means for operating the same in the opposite direction at a high speed, said means being shiftable to reverse the directions of rotation of said forward and reverse threading clutches, for the purpose described.

4. In a machine of the character indicated, a threading spindle, and gear means for normally driving said threading spindle in the forward right hand threading direction at a low speed and in the right hand unthreading direction at a higher speed, said gear means being shiftable to reverse the directions of rotation of said threading spindle while maintaining the speeds substantially the same as before, for the purpose described.

5. In a machine of the character indicated, a

threading spindle drive including a forward threading gear and a reverse threading gear, and slidable gear means for driving said forward threading gear through an idler and driving said reverse threading gear directly and in the opposite direction, said slidable gear means being shiftable to drive said forward threading gear directly in the opposite direction and said reverse threading gear through an idler to reverse the direction of rotation thereof.

6. In a machine of the character indicated, a threading spindle drive including a forward threading gear and a reverse threading gear, a drive shaft, an idler shaft, and meshing gears on said driving and idler shafts for driving said forward threading gear through an idler or directly, depending upon the position of said gears on said driving and idler shafts, and for driving said reverse threading gear either directly or through an idler, depending upon the positions of the gears on said driving and idler shafts, whereby said forward threading gear may be rotated in both directions, and said reverse threading gear may likewise be rotated in both directions, for the purpose described.

7. In a device of the character indicated, a threading spindle, forward and reverse threading clutches, a clutch shift member to control said clutches, a cam roll block carried by said member, and means for automatically releasing said cam roll block from said member whereby the latter may be shifted independently of movement of said cam roll block for the purpose described.

8. In a machine of the character indicated, a shift member, cam engaging means thereon, means for normally holding said member and cam engaging means in fixed relative position, and means for automatically disengaging said cam engaging means and member and shifting said member independently of said cam engaging means.

9. In a machine of the character indicated, a threading spindle, a clutch for said spindle, a clutch shift member for controlling said clutch, cam engaging means carried on said shift member, means for normally holding said cam engaging means and shift member in fixed relative position, and means controlled by the movement of said spindle for automatically releasing said cam engaging means from said shift member.

10. In a machine of the character indicated, a threading spindle, a clutch therefor, a clutch shift member, cam engaging means on said shift member, means for normally holding said cam engaging means and clutch shift member in fixed relative position, and means controlled by the movement of said spindle for releasing said cam engaging means and member and thereafter throwing said member.

11. In a machine of the character indicated, a clutch shift member, cam engaging means on said shift member, pawl mechanism for normally holding said cam engaging means and member relatively to each other, and means for releasing said pawl means whereby said member may be shifted independently of said cam engaging means.

12. In a machine of the character indicated, a shift member, cam engaging means on said shift member, a double pawl device for holding said cam engaging means and member against movement, and means for releasing said pawl device to permit said member to be shifted in

- one direction independently of said cam engaging means.
13. In a machine of the character indicated, a shift member, cam engaging means thereon, holding means for normally holding said shift member and cam engaging means relatively to each other whereby said cam engaging means may be shifted so as to shift said member in one direction, and means for shifting said holding means to release said cam engaging means from said member to permit said member to be shifted in the opposite direction independently of said cam engaging means, and resetting said holding means to hold said cam engaging means relatively to said member whereby said member may be shifted in the reverse direction by said cam engaging means. 80
14. In a machine of the character indicated, a threading spindle, forward and reverse threading clutches, a threading clutch shift member therefor, cam engaging means on said member, means for holding said cam engaging means and member against relative movement in one direction whereby said member may be shifted by said cam engaging means in one direction, and means controlled by the movement of said threading spindle for releasing said cam engaging means from said member and shifting said member independently of said cam engaging means. 85
15. In a machine of the character indicated, a threading spindle, forward and reverse threading clutches, a threading clutch shift lever, cam engaging means thereon, shiftable means for holding said cam engaging means and lever against relative movement in one direction when said shiftable means is in one position and when in another position holding said lever and cam engaging means from relative movement in the opposite direction, whereby said lever may be shifted by said cam engaging means in both directions upon shifting of said shiftable means, and means controlled by the movement of said threading spindle for shifting said shiftable means and throwing said lever. 90
16. In a machine of the character indicated, a threading spindle including concentric spindles shiftable longitudinally of each other, thread leader mechanism for one of said concentric spindles for feeding the latter longitudinally, a second thread leader mechanism for the other of said concentric spindles, and gear means for driving said last mentioned thread leader mechanism. 100
17. In a machine of the character indicated, a pair of concentric threading spindles movable longitudinally relatively to each other, a frame, thread leader mechanism carried by said frame and one of said spindles for feeding one of said spindles, a second thread leader mechanism carried by said frame, and gear mechanism connecting one of said spindles to said second thread leader mechanism, for the purpose described. 105
18. In a machine of the character indicated, concentric threading spindles movable longitudinally relatively to each other, a frame, a pair of thread leader members carried by said frame, a thread leader member carried by one of said spindles and coacting with one thread leader member on said frame for moving one of said spindles, another thread leader member coacting with the other thread leader member on said frame, and gear means connecting one of said last mentioned thread leader members and one of said spindles for feeding one of said spindles. 110
19. In a machine of the character indicated, a threading spindle, a frame, a thread leader member carried by said frame, a coacting thread leader member carried by said spindle, and gear means for driving said first mentioned thread leader from said spindle for feeding the latter. 115
20. In a machine of the character indicated, concentric threading spindles rotatable together but movable longitudinally relatively to each other, a frame, a pair of leader nuts carried by said frame, leader screws coacting with said leader nuts, one of said leader screws being carried directly by one of said spindles, and gear means for connecting the other leader screw to one of said spindles whereby upon rotation of said spindles both will be fed longitudinally by said leader members. 120
21. In a machine of the character indicated, concentric threading spindles rotatable with each other but movable longitudinally relatively to each other, and independent thread leader members for each of said spindles, one of said thread leader members being mounted concentrically with and the other eccentrically of said spindles. 125
22. In a machine of the character indicated, concentric threading spindles rotatable together but movable longitudinally relatively to each other, and thread leader mechanism for feeding said spindles independently of each other, one of said thread leader members being gear driven from one of said spindles. 130
23. In a machine of the character indicated, a threading spindle, a gear carried thereby, a second gear driven by said first mentioned gear, a frame, and coacting thread leader members carried by said frame and said last mentioned gear, whereby upon rotation of said spindle the same will be fed by said thread leader members. 135
24. In a machine of the character indicated, a threading spindle, a frame, a slide guided on said frame, a gear carried by said slide, thread leader mechanism on said gear and frame, and means for rotating said gear from said spindle whereby said slide and spindle will be fed by said thread leader mechanism. 140
25. In a machine of the character indicated, concentric threading spindles rotatable with each other but movable longitudinally relatively to each other, a frame, a thread leader member carried by said frame, a coacting thread leader member carried by one of said spindles and rotatable therewith whereby said spindle will be fed by said coacting thread leader members, a slide on said frame, a gear on the other of said spindles, a second gear meshing with said first mentioned gear and carrying a thread leader member, and a coacting thread leader member carried by said frame, said gears being carried by and movable with said slide whereby upon rotation of said spindles said slide, gears and one of said spindles will be fed by said last mentioned thread leader members. 145
26. In a machine of the character indicated, a threading spindle, a frame, a thread leader member carried by said frame, a second thread leader member coacting with said first mentioned thread leader member on said frame, a slide, and gear means for connecting said second thread leader member to said spindle, said gear means being carried by said slide whereby upon rotation of said spindle said slide, gear means and spindle will be fed by said thread leader members. 150
27. In a machine of the character indicated, a

frame, a turret rotatably mounted thereon, a turret clamp, resilient means for holding said turret clamp in turret clamping position, resilient means for urging said clamp to open position and means accessible from the outside of said frame for adjusting one of said resilient means.

28. In a machine of the character indicated, a frame, a turret rotatably mounted thereon, a turret clamp, means for urging said clamp to open position, resilient means for holding said turret clamp in turret clamping position, and means accessible from the outside of said frame for varying the force exerted by said resilient means.

29. In a machine of the character indicated, a frame, a turret rotatably mounted thereon, a turret clamp, resilient means for urging said turret clamp to open position, resilient means for holding said clamp in turret clamping position, and means accessible from the outside of said frame for varying the force exerted by both of said resilient means.

30. In a machine of the character indicated, a base frame, a head stock thereon, tools rotatably mounted on said head stock, means for advancing said tools, and a turret supported by said frame, said turret having an integral extension supported by said head stock for assisting in supporting and aligning said turret and head stock relatively to each other, and widely adjustable means for said extension for widely varying the gap between said turret and tools.

31. In a machine of the character indicated, a frame, a head stock, a turret mounted on said frame, chucks carried by said turret tools carried by said head stock, cam means on said head stock for advancing said tools, and means for adjustably connecting said turret and said head stock whereby the thrust of said cam means may be resisted by said means adjustably connecting said turret and head stock.

32. In a machine of the character indicated, a head stock, a turret, tools carried by one of said members, chucks carried by the other of said members, means for advancing said tools and chucks relatively to each other, a frame for said turret and head stock, and means connecting said turret and head stock for resisting the collective pressures between said turret and head stock.

33. In a machine of the character indicated, a head stock, a turret, tools carried by one of said members, chucks carried by the other of said members, means for advancing said tools and chucks relatively to each other, a bearing extension extending from said head stock to said turret, and means for adjustably holding said bearing extension against movement in one direction whereby said adjustably held bearing extension resists the combined pressures exerted between said tools and chucks.

34. In a machine of the character indicated, a frame, a head stock thereon, tools on said head-stock, a turret mounted on said frame, a forward bearing extension on said turret and bearing on said head stock, and means for adjustably holding said forward bearing extension on said head stock against movement in one direction whereby separation of said head stock and turret will be resisted by said forward bearing extension, said forward bearing extension being widely adjustable on said head stock to widely vary the gap between said turret and tools.

35. In a machine of the character indicated, a

frame, a head stock thereon, a turret thereon, a central forward bearing extension on said turret and having a bearing in said head stock, means for adjustably holding said forward bearing extension against movement in one direction, and antifriction bearing means to permit said forward bearing extension to rotate freely while being held against said movement in one direction.

36. In a machine of the character indicated, a turret, a head stock, tools carried by one of said members, chucks carried by the other of said members, a central bearing extension between said head stock and turret and rigid with one of said two last mentioned members, and means engaging the other of said two last mentioned members for holding said forward bearing extension against longitudinal movement in one direction whereby the collective pressures exerted between said tools and chucks may be resisted by said central bearing extension.

37. In a machine of the character indicated, a turret, a head stock, a forward bearing extension rigid with one of said members and having a bearing in the other of said members, and means for adjustably holding the bearing end of said forward bearing extension in position against movement tending to separate said head stock and turret, said head stock and turret having a plurality of opposed chucks and tool carriers.

38. In a machine of the character indicated, a frame, a head stock thereon, a turret rotatably mounted on said frame, a forward bearing extension rigid with said turret and having a bearing in said head stock for assisting in supporting and aligning said head stock and turret relatively to each other, means adjustably fixed to said head stock, and antifriction bearing means connecting said means fixed to said head stock and said forward bearing extension, said head stock and turret having opposed chucks and tool carriers, the collective pressures between said chucks and tool carriers being resisted by said forward bearing extension and said means adjustably connected to said head stock.

39. In a machine of the character indicated, a frame, means carrying a tool holder, means carrying a work holder in opposition to said tool holder, means for rotating said tool and work holders relatively to each other, means for advancing said tool and work holders relatively to each other, and means connecting said means carrying said work and tool holders for resisting the tool resistance between said tool and work holders.

40. In a machine of the character indicated, a holder having a plurality of chucks, a corresponding plurality of fluid pressure cylinders carried by said holder, means for conducting pressure fluid to and from said cylinders, valves for controlling the flow of pressure fluid to and from said cylinders, cam means for normally positively holding said valves in one position, and means for serially varying the relative position of said valves and cam means, for the purpose described.

41. In a machine of the character indicated, a holder having a plurality of chucks thereon, a corresponding plurality of fluid pressure cylinders, valves for controlling the flow of pressure fluid to and from said cylinders, cam means for normally positively holding said valves in one position to maintain pressure fluid in said cylinders for holding the chucks controlled.

thereby in closed position, and cam means for serially varying the position of each valve.

42. In a machine of the character indicated, a turret having a plurality of chucks thereon, a corresponding plurality of fluid pressure cylinders carried by said turret, valves for controlling the flow of pressure fluid to and from said cylinders, cam means for normally holding all but one of said valves in definite position to maintain pressure fluid in one end of each of said fluid pressure cylinders, and movable means for throwing each of said valves one at a time to a different position, for the purpose described.

43. In a machine of the character indicated, a turret having a plurality of chucks thereon, a corresponding plurality of fluid pressure cylinders, a head for said cylinders, a valve for each of said cylinders on said head, and cam means for normally positively holding said valves in one position and moving each of said valves one at a time as it reaches a definite station to throw said valve to a different position.

44. In a machine of the character indicated, a turret having a plurality of chucks thereon, a corresponding plurality of fluid pressure cylinders carried by said turret, valves for each of said cylinders and movable with said turret, cam means for holding all but one of said valves in the same definite position, and means for moving the other of said valves to a different position, each of said valves being moved in series as it reaches a definite station.

45. In a machine of the character indicated, a turret having a plurality of chucks, a corresponding plurality of fluid pressure cylinders, valves to control the flow of pressure fluid to and from said cylinders, and cam means for normally maintaining all but one of said valves in position to admit fluid to corresponding cylinders to hold the respective chucks controlled by said cylinders in closed position, said cam means being movable to permit any of said valves to be thrown into a different position in any position of said turret.

46. In a machine of the character indicated, a plurality of fluid pressure cylinders, valves to control the flow of pressure fluid to and from said cylinders, and a cam guard strip for normally maintaining said valves in definite position, said cam guard strip being removable to permit a valve to be moved manually.

47. In a machine of the character indicated, a plurality of fluid pressure cylinders, valves to control the flow of pressure fluid to and from said cylinders, movable cam track means for moving each of said valves in series, and fixed cam track means for maintaining said valves in definite position.

48. In a machine of the character indicated, a plurality of fluid pressure cylinders, valves to control the flow of pressure fluid to and from said cylinders, cam means for holding all but one of said valves in definite fixed position, means for moving the other of said valves to a different position, and fixed cam means for moving said other of said valves to a different position.

49. In a machine of the character indicated, a plurality of fluid pressure cylinders, valves to control the flow of pressure fluid to and from said cylinders, and cam track means for determining the position of said valves, part of said cam track means being movable for varying the position of each of said valves in series.

50. In a machine of the character indicated, a plurality of fluid pressure cylinders, valves to control the flow of pressure fluid to and from

said cylinders, and cam track means for holding all but one of said valves in definite position and permitting the other of said valves to remain in definite position, a part of said cam track means being manually movable to serially vary the position of each of said valves.

51. In a machine of the character indicated, a turret having a plurality of chucks thereon, a plurality of fluid pressure cylinders carried by said turret, annular fluid pressure inlet means, annular fluid pressure outlet means, valve chambers for each of said cylinders in constant communication with said annular fluid pressure inlet and outlet means, valves in said valve casings, and means for shifting said valves to serially control the flow of fluid pressure to and from said cylinders.

52. In a machine of the character indicated, an indexable turret having a plurality of chucks thereon, a corresponding plurality of fluid pressure cylinders, valves for controlling the flow of pressure fluid to and from said cylinders, and cam means fixed against rotation and engaging said valves for positively controlling and maintaining the positions thereof.

53. In a machine of the character indicated, a plurality of fluid pressure cylinders, valves to control the flow of pressure fluid to and from said cylinders, a fixed cam track for normally maintaining some of said valves in definite position, and manually movable cam means for throwing another of said valves.

54. In a machine of the character indicated, a plurality of fluid pressure cylinders, valves to control the flow of fluid to and from said cylinders, and cam track means for normally maintaining some of said valves in definite position and throwing said valves serially to a different position, said plurality of cylinders and said cam track means being relatively rotatable, for the purpose described.

55. In a machine of the character indicated, a plurality of work carriers, a plurality of tool carriers, means for automatically moving some of said tool carriers and opposed work carriers relatively to each other, manual means for moving one of said tool and work carriers relatively to each other, and means for simultaneously rotating said last mentioned tool carrier.

56. In a machine of the character indicated, a frame, a head stock thereon, a plurality of equi-distantly spaced tool carriers thereon, means for rotating all of said tool carriers, a turret having a plurality of work carriers corresponding in number to the tool carriers, means for indexing said turret step by step so as to bring each of said work carriers successively into opposition to each of said tool carriers, manual means connected to one of said rotating tool carriers for manually advancing and reTRACTING said tool carrier relatively to an opposed work carrier, and automatic means for advancing and retracting the other tool carriers relatively to opposed work carriers.

57. In a machine of the character indicated, a head stock, a plurality of tool carriers mounted thereon, means for rotating all of said tool carriers, an indexable turret mounted opposite said head stock and having a plurality of work carriers equal in number to the tool carriers, said work carriers being indexable step by step so as to bring each work carrier into opposition to each tool carrier, manual means detachably secured to said head stock and engaging one of said rotatable tool carriers whereby said tool

- carrier may be manually moved relatively to an opposed work carrier, and automatic means for moving the other of said tool carriers relatively to the other opposed work carriers.
58. In a machine of the character indicated, a plurality of tool carriers, a corresponding plurality of work carriers, means for rotating all of said work and tool carriers relatively to each other, means for indexing said plurality of tool carriers and work carriers step by step so as to bring each of said tool and work carriers opposite each other in succession, manual means for advancing a work and tool carrier relatively to each other when in the loading position, and automatic means for advancing the other work and tool carriers relatively to each other.
59. In a machine of the character indicated, a tool carrier, an opposed work carrier, feed means for moving said tool and work carriers relatively to each other, chucking means, and a member controlling said chucking means upon one movement, said member being connected to said feed mechanism for controlling the latter upon another movement.
60. In a machine of the character indicated, a rotatable tool carrier, a non-rotatable work chuck, feed means for actuating said tool carrier, chucking means for chucking work in said chuck, and a member for controlling said chucking means upon one movement of said member, said member being articulated with said feed means for controlling the latter on another movement of said member.
61. In a machine of the character indicated, a tool carrier, a work carrier, feed means for feeding said work and tool carriers relatively to each other, chucking means for chucking a work piece in said carrier, and a single member connecting said chucking means and feed means for controlling both said chucking means and said feed means upon movement of said member.
62. In a machine of the character indicated, a tool carrier, a work carrier, feed means for moving said tool and work carriers relatively to each other, chucking means for chucking a work piece in said work carrier, and an oscillatable and translatable member connecting said feed means and said chucking means, whereby upon oscillation of said member said chucking means is controlled and upon translation of said member said feed means is controlled.
63. In a machine of the character indicated, a bed, a plurality of tool carriers thereon, a plurality of work carriers opposed to said tool carriers, hydraulic means for chucking work in said work carriers, a tank in said base and divided into two compartments, one for coolant and the other for chuck actuating liquid, a coolant pump, a chucking liquid pump, said coolant compartment being connected to the intake of said coolant pump and receiving coolant from the work, said chuck actuating fluid compartment being connected with the intake of said other pump, and a return conduit for chuck actuating liquid being also connected with said chuck actuating liquid compartment.
64. In a threading device, a frame, a spindle, a thread leader member rotatable by said spindle and held against axial movement thereof, a second thread leader member carried by said frame and coacting with said first thread leader member whereby upon rotation of said spindle said thread leader members will feed the same, a third thread leader member carried by said spindle and rotatable thereby but movable axially relatively thereto, a fourth thread leader member carried by said frame and coacting with said third thread leader member whereby upon rotation of said spindle said third thread leader member will be moved axially, and a spindle concentric with said first mentioned spindle and splined thereto for simultaneous rotation but independent axial movement, said second spindle being connected to said third thread leader member whereby said second spindle will be fed thereby.
65. In a threading device, a frame, a hollow spindle rotatably carried by said frame, a thread leader member slidably but non-rotatably carried by said hollow spindle, a coacting thread leader member carried by said frame, a second spindle within said hollow spindle and connected with said first mentioned thread leader member whereby upon rotation of said hollow spindle said second spindle will be fed by said thread leader members, and mechanism for feeding said hollow spindle.
66. In a threading device, a frame, a hollow spindle journaled in said frame, a pair of thread leader members carried by said frame, a pair of thread leader members coacting therewith and driven by said hollow spindle, a second spindle splined to said hollow spindle so as to be rotatable therewith, said second spindle being connected with one of said last mentioned thread leaders to cause said second spindle to be fed, the other of said last mentioned thread leader members being connected for feeding said hollow spindle.
67. In a threading device, a frame, a pair of concentric spindles splined to each other so as to rotate together and feed independently of each other, a pair of thread leader members carried by said frame, coacting thread leader members driven solely by one of said concentric spindles, all of said thread leader members being supported and actuated wholly independently of one of said concentric spindles, one of said last mentioned thread leader members being connected against axial movement relatively to one of said spindles and the other of said last mentioned thread leader members being connected against axial movement relatively to the other of said spindles, for the purpose described.
68. In a threading device, a frame, a hollow spindle, and a spindle within said hollow spindle, said spindles being splined for simultaneous rotation and independent feeding, a pair of thread leader members driven solely by said hollow spindle and independently of said other spindle, one of said thread leader members being connected to said internal spindle and the other of said thread leader members being connected to said hollow spindle, and a pair of thread leader members carried by said frame and coacting with said first mentioned thread leader members.
69. In a threading device, a frame, a spindle, a thread leader member fixed against axial movement relative to said spindle and rotatable thereby, another thread leader member rotatable by said spindle and splined thereto for axial movement relatively thereto, a second spindle concentric with said first mentioned spindle and connected to said last mentioned thread leader member, said two spindles being splined together for simultaneous rotation but independent axial movement, and thread leader members carried by said frame and coacting

- with said first mentioned thread leader members.
70. In a machine of the character indicated, an indexible carrier, a plurality of chucks indexible therewith, a fluid pressure cylinder and piston for each of said chucks, conduit means for conducting fluid pressure to said cylinders, and means including a manually operable member at the front of the machine for controlling the flow of fluid pressure to each of said cylinders. 80
71. In a machine of the character indicated, an indexible carrier, a plurality of chucks indexible therewith and located at the front of said carrier, a fluid pressure piston and cylinder for each of said chucks and located rearwardly thereof, means for indexing said carrier, fluid pressure conducting means for each of said cylinders, and manually operable means including a handle at the front of the machine for controlling the flow of pressure fluid to the cylinder coacting with the chuck in loading position. 85
72. In a machine of the character indicated, an indexible carrier, a plurality of chucks indexible with said carrier and positioned at the front thereof, a plurality of fluid pressure cylinders, one for each of said chucks, said cylinders being symmetrically disposed and rearwardly of said chucks, a fluid pressure inlet centrally disposed relatively to said cylinders, fluid pressure conducting means for conducting pressure fluid to said cylinders, and a manually operable means for controlling the flow of fluid pressure to each cylinder when it reaches the loading position. 90
73. In a machine of the character indicated, a carrier, a plurality of chucking devices indexible with said carrier located at the front end thereof, a fluid pressure cylinder and piston for each of said chucking devices and located at the rear of said carrier, a chuck actuating rod connecting each said chucking device with the corresponding piston, each said cylinder having fluid pressure conducting means, and manually operable means for reversing the flow of fluid to and from each said cylinder when in the loading position and without disturbing the pressure condition in any of the other cylinders. 95
74. In a machine of the character indicated, an indexible carrier, a plurality of work holders indexible with said carrier, a plurality of tools, means for rotating said work carriers and tools relatively to each other, a fluid pressure cylinder and piston for each of said work holders, fluid pressure conduit means for each cylinder, and manually operable means including a handle at the front of the machine for controlling the flow of fluid to and from each cylinder when in chucking position without disturbing the pressure condition in the others. 100
75. In a machine of the character indicated, a carrier, a plurality of work holders indexible with said carrier, a plurality of tools, means for rotating said work holders and tools relatively to each other, a fluid pressure piston and cylinder for each said work holder for actuating the latter, fluid pressure passage means being normally open to maintain fluid pressure on all of said pistons to maintain said work holders closed, and means including a manually operable member for reversing the pressure condition in the cylinder corresponding to the work holder in loading position whereby the work holder in loading position may be opened. 105
76. In a machine of the character indicated, an indexible carrier, a plurality of work holders indexible with said carrier, a plurality of tools, means for rotating said work holders and tools relatively to each other, a fluid pressure piston and cylinder for each said work holder for actuating the latter, a fluid pressure piston and cylinder for each said work holder for actuating the latter, an individual valve for controlling the flow of pressure fluid to and from each said cylinder, and manually operable means including a handle at the front of the machine for actuating each said valve when it indexes to loading position. 110
77. In a machine of the character indicated, a carrier, a plurality of work holders indexible with said carrier, a fluid pressure piston and cylinder for each said work holder, said cylinders and pistons being arranged symmetrically and at the rear of said carrier, fluid pressure passage means for each cylinder and including a plug member at the rear of said carrier and adjacent said cylinders, and means including a manually operable member for controlling the flow of pressure fluid through the passage means leading to the cylinder corresponding to the work holder in loading position while leaving the pressure condition in the passage means to the other cylinders unchanged. 115
78. In a machine of the character indicated, a threading spindle, a first gear means for driving said spindle at a slow rate in one direction, a second gear means for driving said spindle at a rapid rate in the opposite direction, and means for causing a reversal of the direction of rotation of at least a part of both said first and second gear means for the purpose described. 120
79. In a machine of the character indicated, a threading spindle, a first gear means for driving said spindle at a slow rate in one direction, a second gear means for driving said spindle at a rapid rate in the opposite direction, a part of said gear means being shiftable to cause a reversal of the direction of rotation of at least a part of both said first and second gear means for the purpose described. 125
80. In a machine of the character indicated, a threading spindle, a first drive gear for said spindle, means for rotating said first drive gear at a slow speed and selectively in either direction, a second drive gear for said spindle, means for rotating said second drive gear at a high speed and selectively in either direction but opposite to direction of rotation of said first drive gear, and means for selectively making a driving connection from said first and second drive gears to said spindle for the purpose described. 130
81. In a fluid pressure chucking mechanism, a plurality of chucks, a fluid pressure actuated device for each of said chucks, said fluid pressure actuated devices being symmetrically arranged, supporting means for said chucks and fluid pressure actuated devices, said means being indexible to bring each of said chucks successively into loading position, means including a substantially centrally arranged plug device for conducting pressure liquid to and from said fluid pressure actuated devices, a liquid container from which pressure liquid is drawn and to which it is returned, and a control member for controlling the flow of pressure liquid to and from each of said fluid pressure actuated devices when in loading position, each of said fluid pressure actuated devices being articulated with said control member one after the other in series. 135
82. In a fluid pressure chucking mechanism, a plurality of fluid pressure actuated devices, supporting means therefor, and means for indexing the same to bring each of said fluid pressure ac- 140
75. In a machine of the character indicated, an indexible carrier, a plurality of work holders indexible with said carrier, a plurality of tools, means for rotating said work holders and tools relatively to each other, a fluid pressure piston and cylinder for each said work holder for actuating the latter, fluid pressure passage means being normally open to maintain fluid pressure on all of said pistons to maintain said work holders closed, and means including a manually operable member for reversing the pressure condition in the cylinder corresponding to the work holder in loading position whereby the work holder in loading position may be opened. 145
76. In a machine of the character indicated, an indexible carrier, a plurality of work holders indexible with said carrier, a plurality of tools, means for rotating said work holders and tools relatively to each other, a fluid pressure piston and cylinder for each said work holder for actuating the latter, a fluid pressure piston and cylinder for each said work holder for actuating the latter, an individual valve for controlling the flow of pressure fluid to and from each said cylinder, and manually operable means including a handle at the front of the machine for actuating each said valve when it indexes to loading position. 150

- tuated devices successively into loading position, valve means for controlling the pressure condition in each of said devices, and cam means to cooperate with each said valve when in loading position, said cam means being manually movable to control the pressure condition at will of the fluid pressure actuated device in loading position, said cam being manually movable at any time to position the same to automatically change the pressure condition in the fluid pressure actuated device in loading position when such position is reached.
83. In a fluid pressure chucking mechanism, a carrier, a plurality of chucking devices carried thereby, a fluid pressure actuated device for each of said chucking devices for actuating the latter, a main pressure conduit means having a branch for conducting pressure fluid to each of said pressure actuated devices, a main exhaust conduit means having a branch for conducting exhaust fluid from each of said fluid pressure actuated devices, and valve means for controlling the flow of pressure fluid to and exhaust of pressure fluid from each of said fluid pressure actuated devices, said main pressure conduit means and said main exhaust conduit means being arranged in proximity to each other.
84. In a fluid pressure chucking mechanism, a carrier, a plurality of chucking devices carried thereby, means for indexing said carrier and chucking devices, a fluid pressure actuated device for each said chucking device for actuating the latter, a separate valve for each said fluid pressure actuated device, fluid feed conduit means leading from a common point to each of said valves, and fluid exhaust conduit means leading from each of said valves to a common point.
85. In a fluid pressure chucking mechanism, an indexible carrier, a plurality of chucking devices indexible therewith, a fluid pressure actuated device for each of said chucking devices for actuating the latter, means for indexing said carrier to bring each of said chucking devices successively into loading position, pressure conduit means for conducting pressure fluid to each of said pressure actuated devices, exhaust conduit means for conducting exhaust fluid from each of said fluid pressure actuated devices, said pressure conduit means being collected at a common point substantially centrally of said carrier, and said exhaust conduit means being collected at a common point substantially centrally of said carrier, and means for controlling the flow of pressure fluid to and exhaust of pressure fluid from each of said fluid pressure actuated devices in loading position.
86. In a fluid pressure actuated chucking mechanism, an indexible carrier, a plurality of chucking devices indexible therewith, a fluid pressure actuated device for each said chucking device, means for indexing said carrier, pressure conduit means substantially centrally of said carrier and having a branch leading to each of said fluid pressure actuated devices for conducting pressure fluid thereto, exhaust conduit means adjacent said first mentioned conduit means and substantially centrally of said carrier, said exhaust conduit means having a branch leading to each of said fluid pressure actuating devices, and valve means for controlling the admission of pressure fluid to and exhaust from each of said fluid pressure actuated devices.
87. In a fluid pressure chucking mechanism, an indexible carrier, a plurality of chucking devices symmetrically arranged and indexible therewith, a fluid pressure actuated device for each of said chucking devices for actuating the latter, pressure conduit means arranged substantially centrally of said carrier and fluid pressure actuated devices and having a branch leading to each of said fluid pressure actuated devices, exhaust conduit means arranged substantially centrally of said carrier and fluid pressure actuated devices and having a branch leading to each of said fluid pressure actuated devices, and a valve for each of said fluid pressure actuated devices for controlling the admission of pressure fluid to and exhaust of pressure fluid from each of said fluid pressure actuated devices.
88. In a fluid pressure chucking mechanism, an indexible carrier, a plurality of chucking devices symmetrically arranged about said carrier and movable therewith, a cylinder and piston for each said chucking device and movable with the latter, means for indexing the aforementioned parts to successively bring each chucking device to loading position, main pressure fluid conduit means and main exhaust fluid conduit means common to all of said cylinders, and valve means operable to exhaust pressure fluid from and admit pressure fluid to each of said cylinders successively in loading position.
89. In a fluid pressure chucking mechanism, an indexible carrier, a plurality of chucking devices indexible therewith, a fluid pressure cylinder and piston for each said chucking device and movable therewith, annular fluid pressure inlet means, annular fluid pressure outlet means, valve chambers for each of said cylinders in constant communication with said annular fluid pressure inlet and outlet means, valves in said valve casings, and means for serially shifting said valves to control the flow of pressure fluid to and from said cylinders.
90. In a fluid pressure chucking mechanism, an indexible carrier, a plurality of chucking devices indexible therewith, a fluid pressure actuated device for each of said chucking devices, means for indexing said carrier to bring each of said chucking devices successively into loading position, plug means arranged substantially centrally of said fluid pressure actuated devices, said plug means defining fluid conduit means for conducting pressure fluid to and exhausting the same from each of said fluid pressure actuated devices, control means for controlling the admission of pressure fluid to and exhaust pressure fluid from each of said fluid pressure actuated devices when in loading position, and a manually operable handle permanently carried by said frame, together with means for connecting the same to said control means for moving the latter.
91. In a fluid pressure chucking mechanism, a frame, a carrier indexibly mounted thereon, a plurality of chucking devices indexible with said carrier, a fluid pressure actuated device for each of said chucking devices for actuating the latter, means for indexing said carrier to bring each of said chucking devices successively to loading position, means for conducting pressure fluid to each of said fluid pressure actuated devices, control means for controlling the flow of pressure fluid to and exhaust of pressure fluid from each of said fluid pressure actuated devices when in loading position, and a manually operable handle permanently carried by said frame together with means connecting said

handle and control means for moving the lat-
ter.

92. In a fluid pressure chucking mechanism, a frame, a carrier indexibly mounted on said frame, a plurality of chucking devices indexible with said carrier, a fluid pressure cylinder and piston for each of said chucking devices, said chucking devices being located axially forwardly of said carrier and said fluid pressure cylinders and pistons being located axially rearwardly of said carrier, fluid pressure connections to each of said cylinders, means for controlling the pressure condition in each of said cylinders serially when indexed to loading station, said means including a manually operable member located axially forwardly of said cylinders so as to be within convenient reach of an operator in front of said chucks.

93. In a fluid pressure chucking mechanism, a frame, a carrier indexibly mounted on said frame, a plurality of chucking devices indexible with said carrier, a fluid pressure cylinder and piston for each of said chucking devices, said chucking devices being located axially forwardly of said carrier, and said fluid pressure cylinders and pistons being located axially rearwardly of said carrier, fluid pressure connections to each of said cylinders, a separate control valve for each of said cylinders, means for actuating each of said valves serially for controlling the pressure condition in each of said cylinders serially when indexed to loading station, said means including a manually operable member located axially forwardly of said cylinders so as to be within convenient reach of an operator in front of said chucks.

94. In a fluid pressure chucking mechanism, a frame, a carrier indexibly mounted on said frame, a plurality of chucking devices indexible with said carrier, a fluid pressure cylinder and piston for each of said chucking devices, said chucking devices being located at one end of said carrier and said fluid pressure cylinders and pistons being located adjacent the opposite end of said carrier, fluid pressure connections to each of said cylinders, means for controlling the pressure condition in each of said cylinders serially when indexed to loading station, said means including a manually operable member located remote from said cylinders and toward said chucks so as to be within convenient reach of an operator adjacent said chucks.

95. In a fluid pressure chucking system, a frame, a carrier indexibly mounted on said frame, a plurality of chucking devices indexible with said carrier, a fluid pressure cylinder and piston for each said chucking device and indexible therewith, means for conducting pressure fluid to each of said cylinders, a valve to control the flow of pressure fluid to and exhaust of pressure fluid from each of said cylinders, said valves being indexible with said cylinders, a manually operable handle carried by said frame and located within convenient reach of an operator, and means operable by said handle and positioned adjacent the said valves when in loading station and cooperable therewith, whereby each valve when in loading station may be manually operated at will by said handle to change the pressure condition in its correspond-
ing cylinder.
